[57] CLAIM

The ornamental design for a remote vehicle disabling switch, as shown and described.

DESCRIPTION

FIG. 1 is a left side elevational view of the remote vehicle disabling switch of the present invention, the right side elevational view being a mirror image thereof;

FIG. 2 is a rear elevational view of the remote vehicle disabling switch of FIG. 1;

FIG. 3 is a front elevational view of the remote vehicle disabling switch of FIG. 1;

FIG. 4 is a top plan view of the remote vehicle disabling switch of FIG. 1; and,

FIG. 5 is a bottom plan view of the remote vehicle disabling switch of FIG. 1.
